J. M. PATTERSON.

WINDOW SHADE.

APPLICATION FILED MAY 22, 1908.

914,180.

Patented Mar. 2, 1909.

UNITED STATES PATENT OFFICE.

JOHN M. PATTERSON, OF LA FAYETTE, GEORGIA.

WINDOW-SHADE.

No. 914,180.

Specification of Letters Patent.

Patented March 2, 1909.

Application filed May 22, 1908. Serial No. 434,431.

To all whom it may concern:

Be it known that I, JOHN M. PATTERSON, a citizen of the United States, residing at La Fayette, in the county of Walker and State of Georgia, have invented a new and useful Window-Shade, of which the following is a specification.

This invention relates to window shades and its object is to provide means whereby 10 the shade can be either raised from the bottom or lowered from the top of a window, or both raised from the bottom and lowered from the top at the same time, means being provided whereby the shade can be firmly 15 held in any position to which it may be adjusted.

Another object is to provide a shade designed to be rolled from either end, novel 20 means being provided for actuating the rollers and for maintaining them at all times in operative positions.

A further object is to provide brackets of novel form for use in connection with the shade fixtures and whereby curtain poles can 25 be conveniently supported.

With these and other objects in view the invention consists of certain novel features of construction and combinations of parts which will be hereinafter more fully described 30 and pointed out in the claims.

In the accompanying drawings is shown the preferred form of the invention.

Figure 1 is a perspective view of a shade and fixtures embodying the present improvements. Fig. 2 is a longitudinal section 35 through one of the cord clips. Fig. 3 is a vertical section through one of the upper brackets of the fixture. Fig. 4 is a horizontal section showing a modified construction. Fig. 5 is a front view of one of the brackets of 40 the fixture.

Referring to the figures by characters of reference, A designates a window casing and arranged longitudinally upon each side thereof is a rack 1 preferably formed of an elongated flat metal strip crimped transversely to form teeth although it is to be understood that any preferred construction may be used in lieu of the strip 1. Each strip 1 extends 45 throughout the height of the window casing and arranged at the lower end of each strip is an outstanding L-shaped bracket 2 having a slot 3 therein for the reception of a tongue 4 extending from and formed at one end of a 50 guide or retaining bar 5 arranged parallel with and in front of the adjoining strip 1.

This bar is preferably in the form of a flat strip of metal increasing in width toward the center thereof. The upper end of the bar extends into a slot 6 formed in a bracket 7 secured to the top portion of the window casing and this bracket has a laterally extending inverted U-shaped extension 8 in which is mounted a sheave 9. A retaining clip 10 is pivoted upon the bracket 7 and is disposed to swing laterally so as to overhang and bear upon the upper end of bar 5 or to be swung in the opposite direction so as to uncover the end of said bar.

Each rack 1 is engaged by a gear 11 having flanges upon the faces thereof and extending beyond the teeth, said flanges being indicated at 12 and designed to extend across opposite faces of the rack and of the adjoining retaining bar. The two gears 11 are 75 connected by a roller 13 having hooks 14 thereon designed to detachably engage the upper end portion of a flexible curtain 15. A drum 16 is secured upon the outer face of one of the gears 11 and has a cord or other 80 flexible device 17 fastened to it and extending upward over the sheave thereabove and thence downward to the bottom of the window casing.

Arranged below the gears 11 and upon the respective racks 1, 1 are gears 18 each having annular flanges extending to opposite sides of the adjoining racks and retaining bars and these gears are secured to the ends of a roller 19 to which the lower end of the shade fixture is fastened. A drum 20 is secured to the outer face of one of these gears and has a cord or other flexible device connected thereto and extending upward to and over the other sheave of the fixture, it being understood, of course, that the drums 16 and 20 are located at opposite sides of the window shade.

Secured to the window casing at each side of the opening therein is a clip for holding the adjoining cord in shifted position. Each clip consists of a forked body 22 of spring metal secured at its ends to the casing while a head 23 substantially V-shaped, extends from this body and has a finger piece 24 at the end thereof so that it can be conveniently manipulated. Each cord 17 and 21 extends through the fork of one of these clips and is designed to be pressed against the casing by the head 23. In order, however, that the head may be prevented from pressing too far into the cord and thus injuring it through

continued use, a roller 25 is carried by the forked body 22 close to head 23 and bears upon the cord as shown in Fig. 2 so as to limit the frictional engagement by the head with the cord. A guide loop or staple 26 is secured to each side of the window casing and constitutes a cord guide. In order to prevent the cord of the lower drum 20 from jumping off of said drum as for example, when the roller is suddenly lowered, an arm 27 is secured to the casing A and extends into the path of the drum so that when said drum reaches its lowest position this arm will extend thereacross and act as a guard to prevent the cord from leaving the drum should it become slack.

It is of course to be understood that the cords 17 and 21 are normally partly wound upon their respective drums. When it is desired to unroll the upper end of the shade the operator pulls downward on cord 17 so that it will slide under the roller 25 and the head 23, and will pull upward on the drum 16 and at the same time unwind therefrom. The drum will thus be rotated and the gears 11 will travel upwardly upon the racks 1, the roller at the same time unwinding the shade. The roller will be held in adjusted position by the pressure of the clip head 23 upon the cord. To raise or roll the lower end of the shade the lower roller is manipulated in the same manner by means of its cord 21. To lower either of the rollers and wind or unwind the shade, the cord of the roller is released by lifting the spring clip out of engagement therewith. Obviously, during the up and down movements of the rollers the gears are held in mesh with the racks by the bars 5. Each bar can be readily detached from its brackets by swinging the retaining clip off of the end thereof. The bar can then be elevated a short distance within the opening 6 so as to withdraw its tongue 4 from the slot 3. The bar can then be lowered and thus withdrawn from the slot 6. After both bars have been removed in this manner the rollers and the gears connected thereto can be easily taken from or placed in position.

As shown in Fig. 3 a bracket 28 for supporting a curtain pole may be detachably mounted upon each extension 8 of brackets 7. This bracket 28 has a body strip 29 designed to rest upon the extension 8 and having its free end inturned as at 30 while its other end is also inturned or depressed as shown at 31 so that the bracket can be readily sprung over extension 8 as clearly indicated.

Instead of providing flat guide and retaining bars such as shown at 5, rods 32 may be utilized in which event it is necessary to use reinforcing arms 33 at points between the ends of the rod. These arms are soldered or otherwise secured to the rod and are detach-

ably fastened to the window casing and, when thus secured, serve to prevent the rods from springing outwardly and releasing the gears from mesh with the racks.

What is claimed is:

1. The combination with parallel racks, brackets adjacent the ends thereof, and combined guide and retaining devices detachably supported by the brackets; of rollers arranged one above the other, a shade secured at its ends thereto, gears upon each roller and interposed between the racks and retaining devices, a drum upon each roller, and flexible means for rotating each drum to shift it vertically.

2. In a shade fixture the combination with a rack and slotted brackets outstanding from the ends thereof; of a retaining bar seated at its ends within the slots and parallel with the rack, said bar bearing upon the lower bracket and a retaining clip movably mounted upon the other bracket and normally bearing upon the end of the bar.

3. In a shade fixture the combination with a rack and superposed slotted brackets adjacent the ends thereof; of a retaining bar having its upper end seated within the slot in the upper bracket, there being a tongue at the lower end of the bar and seated in the slot in the lower bracket, and a shiftable retaining clip upon the upper bracket and bearing upon the end of the bar.

4. In a shade fixture the combination with a bracket having an inverted U-shaped extension, and a sheave within the extension; of a pole supporting bracket, having a body strip, there being inwardly directed means upon said strip for embracing and frictionally engaging opposite edges of the inverted extension.

5. The combination with parallel racks, and brackets secured adjacent the upper and lower ends of the racks; of combined guide and retaining devices supported by the brackets and parallel with the racks, upper and lower rollers, a shade secured at its ends to, and disposed to be wound upon both of the rollers, gears carried by the rollers, and mounted to travel upon the racks and between the racks and retaining strips, a drum upon one end of each roller, flexible actuating devices connected to and disposed to be wound upon the respective drums, and guide wheels carried by the upper brackets and supporting said flexible devices.

In testimony that I claim the foregoing as my own, I have hereto affixed my signature in the presence of two witnesses.

JNO. M. PATTERSON.
